DESIGN FOR A DISPLAY CARD HOLDER OR THE LIKE

Lawrence P. Woodward, Chicago, Ill.

Application August 10, 1945, Serial No. 121,373

Term of patent 14 years

(Cl. D80—9)

To all whom it may concern:

Be it known that I, Lawrence P. Woodward, a citizen of the United States, residing at Chicago, in the county of Cook and State of Illinois, have invented a new, original, and ornamental Design for a Display Card Holder or the like, reference being had to the accompanying drawing, forming a part thereof.

In the drawing:

Fig. 1 is a front elevational view of a display card holder showing my new design.

Fig. 2 is a side elevation thereof; and
Fig. 3 is a top plan view thereof.

I claim:

The ornamental design for a display card holder or the like, as shown.

LAWRENCE P. WOODWARD.
